UNITED STATES PATENT OFFICE.

JEWETT HORTON, OF PHILMONT, NEW YORK.

DESIGN FOR A FAUCET-BODY.

SPECIFICATION forming part of Design No. 25,977, dated August 25, 1896.

Application filed April 3, 1896. Serial No. 586,130. Term of patent 14 years.

To all whom it may concern:

Be it known that I, JEWETT HORTON, a citizen of the United States, residing at Philmont, in the county of Columbia and State of New York, have invented and produced a new and original Design for a Faucet-Body, of which the following is a specification, reference being had to the accompanying drawing, showing a part thereof.

10 In the accompanying drawing, forming a portion of this specification, is shown a side elevation of the body portion of the faucet constructed in accordance with my design.

My design consists of a cylindrical body portion A, having one extremity B turned at 15 an angle thereto, said upturned portion being also cylindrical and provided with transverse annular corrugations. The opposite extremity C of the body is turned in a different direction from the extremity B, as shown, the

angle of which turn being in excess of the angle between the body portion A and the upturned end B. The extreme end of the extremity C is somewhat enlarged at D, forming in effect an annular flange. 25

The leading feature of my design is the body portion, having its extremities turned at an angle thereto, substantially as shown and described.

Having thus described my invention, what I claim is— 30

The design for a faucet-body, substantially as shown and described.

In witness whereof I affix my signature in the presence of two witnesses.

JEWETT HORTON.
